SLICING MACHINE

William J. Campbell, Indianapolis, Ind., assignor
to American Slicing Machine Company, Chi-
cago, Ill., a corporation of New York

Application January 7, 1931, Serial No. 507,171

10 Claims. (Cl. 146—102)

My invention relates to a slicing machine of the type in which a knife, for example a rotary knife, is associated with an upright guard plate, a gauge plate generally parallel with the guard plate, and a work supporting carriage for conveying the work past the cutting edge of the knife in general parallelism with carriage and guard plate. One object of my invention is the provision of an improved form of the control or actuating means for a pusher plate on the carriage. Another object is the provision of manual means for permitting or causing the pusher plate to move yieldingly forwardly toward the carriage plate when the carriage is returning, after a cutting excursion, to position for beginning the following cutting excursion. Another object is the provision of means for limiting the forward movement of the pusher plate, together with manually operable means, for interrupting such limiting means. Other objects will appear from time to time in the course of the specification and claims.

I illustrate my invention more or less diagrammatically in the accompanying drawings, where-

25 Figure 1 is an end elevation with parts in section;

Figure 2 is a front elevation;

Figure 3 is a partial plan view;

30 Figure 4 is a section on the line 4—4 of Figure 2;

Figure 5 is a section on the line 5—5 of Figure 4;

Figure 6 is a section on the line 6—6 of Figure 1;

Figure 7 is a partial end elevation of the carriage illustrating a variant form of guard member; and

Figure 8 is a section on the line 8—8 of Figure 7.

Like parts are indicated by like symbols throughout the specification and drawings.

Referring to the drawings, A generally indicates any suitable slicing machine base, mounted for example on yielding struts A¹. A² is an upstanding frame portion upon which may be mounted, in any suitable fashion, the rotary knife A³ and the forward guard plate therefor A⁴. A⁵ indicates a motor which may drive the knife A³ through the pulley A⁶, the belt A⁷ and the pulley A⁸.

B indicates a gauge plate which may be mounted in any suitable fashion, for example on links B¹, responsive to the rotation of the manual con-

trol knob B³, whereby the gauge plate may be moved toward and away from the cutting plane.

C is any suitable cover member.

D is a cylindrical track along which is slidable the carriage structure, generally indicated as D¹. D² is a rectangular guide track, herein shown as vertically aligned beneath the track D. It may be engaged, for example by the downward extension D³ of the carriage structure which serves to prevent unintended rotation of the carriage about the track D. Any suitable take-up means may be employed, such as the screw D⁴ and the nut D⁵. The form of carriage herein illustrated is shown as including a work supporting and guiding trough D⁶, including the walls D⁷ and D⁸.

5 Mounted on the carriage structure D¹ and extending outwardly therefrom adjacent the supporting wall or face D⁸, is a hollow guide pin or rod E, the inner end of which is screw threaded as at E¹ to be screwed into the screw threaded apertures E² in the carriage D¹. Its end is enlarged as at E³ to serve as a bearing and stop portion for an outer cylindrical sleeve E⁴. The sleeve E⁴ is inwardly reduced as at E⁵, the portions E³ and E⁵ respectively being adapted to stop or limit the outward movement of the sleeve E⁴ in relation to the shaft E. A spring E⁶ is anchored at one end to the screw threaded plug E⁷ which closes the outer end of the sleeve E⁴. It is anchored at the other end to an abutment or eye E⁸, as shown for example in Figure 4.

20 Slidably mounted upon the exterior sleeve E⁴ is any suitable pusher plate structure, including a sleeve G, a projection G¹ therefrom, a pin G² mounted in said projection, and a pusher plate G³ mounted upon said pin, as by the bracket G⁴. The pin G² is preferably rotatable in relation to the arm G¹, passing for example through a sleeve G⁵.

25 Interposed between the shaft E and the outer sleeve E⁴ is the following locking arrangement. A collar H is secured to the inner end of the sleeve E⁴ and includes an inwardly projecting portion H¹, having a beveled or conic locking surface H². The member H also includes a seat H³ for a spring H⁴ which surrounds the member H. The opposite end of the spring engages the inward projection H⁶ of the generally cylindrical member H⁵, shown as exteriorly knurled as at H⁷. Its opposite end is closed by the screw threaded plug H⁸, which is somewhat spaced from the shaft E and has a cylindrical ring or flange projecting within the conic locking seat 30

50 55

H^2 . This flange is broken by a plurality of apertures H^{10} , in which seat balls H^{11} . As will be seen from Figure 4, these balls engage the interior surface of the conic seat H^2 . The effect 5 of the spring is to thrust the balls inwardly along the shaft E against the conic locking seat H^2 . Thus the normal effect of the spring is to hold the sleeve E^4 against longitudinal movement in relation to the shaft E , and a manual movement 10 of the locking assembly is necessary, in order to free the balls H^{11} from their locking relationship, to permit the spring E^6 to move the pusher plate structure inwardly toward the cutting plane.

15 It will be understood, as from the full line and dotted line illustration in Figure 2, that the pusher plate may be swung into inoperative position below the carriage, in which position it may be held as by the abutment J , with its forward 20 tapered nose J^1 and its securing circumferential aperture J^2 , in which the edge of the pusher plate may sit. In order to prevent the pusher plate from battering the bottom of the carriage structure, I may provide one or more guard members, 25 such as are shown as at J^3 , J^4 , which prevent the edge of the pusher plate from contacting the bottom of the carriage. These guard members may be integral, as shown in Figure 6, or may be separately formed, as shown in Figures 7 and 8.

30 It will be realized that whereas I have described and shown a practical and operative device, that nevertheless many changes may be made in size, shape, number and disposition of parts without departing from the spirit of my invention. I 35 wish my drawings, therefore to be taken as in a broad sense illustrative and diagrammatic, rather than as limiting me to my specific showing herein.

The use and operation of my invention are as follows:

40 The spring E^6 normally tends to move the pusher plate structure G^3 toward the cutting plane, thus moving the work positively against the gauge plate and guard plate. However, it is desirable, when the work is set against the gauge plate, to prevent any additional pressure or continuing spring pressure against the guard plate after the slice is severed. I therefore provide locking means, including the spring H^4 , which resists the movement of the spring E^6 . The locking 45 means may be released to permit the normal gauging thrust, as by manual movement of the knurled portion of the sleeve H^5 , permitting the work to be positioned firmly against the gauge plate. For example a manual forward thrust of 50 the knurled member moves the balls H^{11} out of their locking connection between the opposed surfaces of the members H and E , the spring H^4 being compressed. Then the slicing excursion is made, but the spring E^6 cannot move the work 55 forwardly until the operator again releases the locking means. This he may do at the end of the return excursion, again permitting the spring E^6 to advance the work against the gauge plate. The locking means keeps the material upon the 60 carriage out of contact with the guard plate, knife and gauge plate during the return excursion and thus prevents larding of said members; this also reduces to a minimum sliding or rubbing of the work against a surface which results in cleaner 65 looking slices.

I claim:

1. In a slicing machine which includes a knife and means for actuating it, a gauge plate and a guard plate lying in generally parallel planes, a carriage and means for guiding the carriage

across the faces of gauge and guard plates and past the cutting edge of the knife, a pusher plate mounted on said carriage and normally movable toward and away from the cutting plane, spring means for urging the pusher plate toward the cutting plane of the knife, self-locking means tending normally to lock the pusher plate urging means against movement towards the knife while leaving the same free to be retracted, said locking means including a one-way clutch mechanism 10 biased to clutching position, and a manually operable clutch control element for releasing said clutch to permit said spring means to advance the pusher plate.

2. In a slicing machine which includes a knife 15 and means for actuating it, a gauge plate and a guard plate lying in generally parallel planes, a carriage and means for guiding the carriage across the faces of gauge and guard plates and past the cutting edge of the knife, a pusher plate, 20 means for mounting the pusher plate on the carriage for movement toward and away from the cutting plane of the knife including a guide member fixedly mounted on the carriage, a sleeve member slidably mounted upon said fixed guide, 25 said pusher plate being mounted upon said sleeve, yielding means normally tending to move the sleeve and pusher plate toward the cutting plane, self-locking means tending normally to secure the sleeve and guide to lock the sleeve against movement toward the cutting plane while leaving the same free to be retracted, and means manually to release said locking means to allow the yielding means to advance the pusher plate.

3. In a slicing machine which includes a knife 30 and means for actuating it, a gauge plate and a guard plate lying in generally parallel planes, a carriage and means for guiding the carriage across the faces of gauge and guard plates and past the cutting edge of the knife, a pusher plate, 35 means for mounting the pusher plate on the carriage for movement toward and away from the cutting plane of the knife and including a guide fixed on the carriage, a guide for the pusher plate axially movable in relation to said fixed guide, the 40 pusher plate being mounted upon said last mentioned guide, yielding means normally tending to move the movable guide and pusher plate toward the cutting plane, self-locking means including a one-way clutch biased to clutching position 45 interposed between the fixed and the movable guide members and tending to relatively secure said members to lock the movable guide against movement toward the cutting plane of the knife while leaving it free to be retracted, and a manually 50 operable clutch control element for releasing the clutch to permit the yielding means to advance the movable guide and pusher plate.

4. In a slicing machine which includes a knife and means for actuating it, a gauge plate and a 55 guard plate lying in generally parallel planes, a carriage and means for guiding the carriage across the faces of gauge and guard plates and past the cutting edge of the knife, a pusher plate, 60 means for mounting the pusher plate on the carriage for movement toward and away from the cutting plane of the knife and including a guide fixed on the carriage, a guide for the pusher plate axially movable in relation to said fixed guide, the 65 pusher plate being slidably mounted upon said last mentioned guide, yielding means normally tending to move the movable guide and pusher plate toward the cutting plane, a one-way clutch mechanism interposed between the fixed and movable guide members biased to clutching 70 upon said last mentioned guide, yielding means normally tending to move the movable guide and pusher plate toward the cutting plane, a one-way clutch mechanism interposed between the fixed and movable guide members biased to clutching 75

position and tending normally to secure the guide members together to lock the movable guide against movement towards the knife while leaving the pusher plate free to be retracted, and a manually operable clutch control element to release said clutch to permit the yielding means to advance the pusher plate.

5. In a slicing machine which includes a knife and means for actuating it, a gauge plate, a carriage and means for guiding the carriage across the face of the gauge plate and past the cutting edge of the knife, a pusher plate mounted on said carriage and normally movable toward the cutting plane, guiding means for said pusher plate including a hollow sleeve normally fixed in relation to the carriage, a surrounding sliding sleeve slidable on said first mentioned hollow sleeve, yielding means tending normally to move said last mentioned sleeve, and the pusher plate with it, 10 toward the cutting plane, and self-setting brake means adapted normally to resist such movement of the last mentioned sleeve, said brake means being effective throughout a wide range of positions of the outer sleeve, the pusher plate being 15 slidably and rotatably mounted upon the outer sleeve, and manually operable means for rendering the brake means inoperative, to permit the pusher plate to be advanced toward the cutting plane.

20. 6. In a slicing machine which includes a knife and means for actuating it, a gauge plate, a carriage and means for guiding the carriage across the face of gauge plate and past the cutting edge of the knife, manual means for moving said carriage, a guide on said carriage, generally perpendicular to the cutting plane, a plate mounted for movement along said guide toward and away from the cutting plane, means tending normally to urge the plate along the guide toward the cutting plane and self-acting friction brake means, associated with the plate and guide, tending normally to resist such movement of the plate, said 25 brake means including a member surrounding said guide, a plurality of roller elements interposed between said member and said guide, and yielding means for directing locking pressure against said roller elements, and manual control means, independent of the manual carriage moving means, operable to release said brake means whereby said plate moving means may advance the plate said brake means being effective at a 30 wide range of positions of the plate, and being effective at all times except during the period of manual manipulation of the direct manual control means.

55. 7. In a slicing machine which includes a knife and means for actuating it, a carriage and means for guiding the carriage past the cutting edge of the knife, a pusher plate mounted on said carriage and normally movable toward and away from the cutting plane, spring means for urging the pusher plate toward the cutting plane of the knife, self-locking means tending normally to lock the pusher plate urging means against movement toward the knife while leaving the same free to be retracted, said locking means, independent of movement of the carriage along its path, including a one-way mechanism biased to clutching position, and a manually operable clutch control element for releasing said clutch at any position of the carriage to permit said spring means to advance the pusher plate.

8. In a slicing machine which includes a knife and means for actuating it, a carriage and means for guiding the carriage past the cutting edge of the knife, a pusher plate, means for mounting the pusher plate on the carriage for movement toward and away from the cutting plane of the knife, including a guide member fixably mounted on the carriage, a sleeve member slidable mounted upon said fixed guide, said pusher plate being mounted upon said sleeve, yielding means 10 tending normally to move the sleeve and pusher plate toward the cutting plane, self-locking means tending normally to secure the sleeve and guide to lock the sleeve against movement toward the cutting plane while leaving the same free to 15 be retracted, said locking means being effective at all positions of the carriage along its path, and means manually to release said locking means to allow the yielding means to advance the pusher plate, said last mentioned releasing means being 20 independent of the position of the carriage.

9. In a slicing machine which includes a knife and means for actuating it, a carriage and means for guiding the carriage past the cutting edge of the knife, a pusher plate, means for mounting the pusher plate on the carriage for movement toward and away from the cutting plane of the knife and including a guide fixed on the carriage, a guide for the pusher plate axially movable in relation to the fixed guide, the pusher plate being 25 mounted upon said last mentioned guide, yielding means normally tending to move the movable guide and pusher plate toward the cutting plane, self-locking means including a one-way clutch biased to clutching position interposed between 30 the fixed and the movable guide members and tending to relatively secure said members to lock the movable guide against movement toward the cutting plane of the knife while leaving it free to be retracted, said locking means being effective at 35 all positions of the carriage along its path, and a manually operable clutch control element for releasing the clutch to permit the yielding means to advance the movable guide and pusher plate, said last mentioned releasing means being independent 40 of the position of the carriage.

10. In a slicing machine which includes a knife and means for actuating it, a carriage and means for guiding the carriage past the cutting edge of the knife, a pusher plate, means for mounting the pusher plate on the carriage for movement toward and away from the cutting plane of the knife and including a guide fixed on the carriage, a guide for the pusher plate axially movable in relation to said fixed guide, the pusher plate being 50 slidably mounted upon said last mentioned guide, yielding means normally tending to move the movable guide and pusher plate toward the cutting plane, a one-way clutch mechanism interposed between the fixed and movable guide members biased to clutching position and tending normally to secure the guide members together to lock the movable guide against movement toward the knife but leaving the pusher plate free to be retracted, said locking means being effective at 55 all positions of the carriage along its path, and a manually operable clutch control element to release said clutch to permit the yielding means to advance the pusher plate, said last mentioned releasing means being independent of the position 60 of the carriage.

70 WILLIAM J. CAMPBELL.
